UNITED STATES PATENT OFFICE.

SHORTRIDGE HARDESTY, OF LARCHMONT, NEW YORK, ASSIGNOR TO WADDELL & HARDESTY, OF NEW YORK, N. Y., A COPARTNERSHIP CONSISTING OF JOHN A. L. WADDELL AND MYSELF.

COUNTERBALANCING MEANS FOR LIFT BRIDGES.

Application filed February 17, 1927. Serial No. 168,860.

Lift bridges of various sorts which are counterweighted are subject to a variation in the counterbalancing loads as the span rises and falls.

5 The invention herein described aims to counterbalance these varying loads or strains. The accompanying drawings illustrate embodiments of the invention.

Fig. 1 is a side elevation of a vertical lift 10 bridge;

Fig. 2 is a side elevation of one end of the same with a modified counterbalancing arrangement.

The lift span and other moving parts are 15 shown in full lines in the lowered position of the bridge and in dotted lines in the raised position. The span 1 moves vertically between towers 2. Various arrangements of motor and connections are used for lifting 20 and lowering such spans. These are not illustrated in the present case. The weight of the lift span is taken off the motor by means of cables 3 leading from the ends of the span up to pulleys 4 at the tops of the 25 towers and over such pulleys and down to counterweights 5. As the span rises the length of the inner portion of the cable 3 is lessened and the length of the outer portion, the end connected to the counterweight, is 30 increased, so that the uplifting or counterbalancing effect increases. And conversely, on the downward movement of the span the counterbalancing load decreases.

The main counterbalancing cables are of 35 considerable weight and there is consequently a considerable variation in the load on the motor.

According to this invention, such variation of the loads on the span is counterbalanced in whole or in part. For this purpose 40 the vertical movement of the span is utilized to change the direction of a stress applied to it by supplementary counterbalancing means; such change in direction being accompanied by a change in the vertical component of the stress or load. The principle 45 may be applied in a great variety of ways.

According to Fig. 1, supplementary counterbalancing cables 6 are connected to the top 50 chord of the span at points somewhat distant from the ends and lead over pulleys 7 near the tops of the towers and down to supplementary counterweights 8. The number and dimensions of these supplementary counter-

weighting devices will be adjusted according 55 to the weights of the span and the main counterweights and their cables. In the lowered position of the span, the strain on the cable 6 is nearly vertical. The vertical component or lifting effect on the span is, 60 therefore, nearly equal to the weight of the counterweight 8. In the highest position of the span, the cable 6 is nearly horizontal; and the vertical component of the pull on the span is very slight. The difference 65 between the vertical components in the two extreme positions may be made equal to the variation in the pull of the main counterweights 5; the pull from the supplementary counterweight decreasing as that from the main 70 counterweight increases.

According to Fig. 2, the main counterweighting system is the same as for Fig. 1, but the supplementary counterbalancing 75 scheme is different. Cables 9 are connected to the span 1 near its end and are led through guide blocks 10 to pulleys 11 fastened on the towers 2 at points between the extreme lower and upper positions of the span. The relative location of the guide pulley 11 and the 80 point of connection of the cable to the lift span ensures an even greater change in the direction in which the pull of the counterweight is applied to the span than in Fig. 1.

In the latter the pull is applied always 85 upward and with a varying degree of obliquity; in Fig. 2, the pull of the supplementary counterweights is upward during a part of the rise of the lifting span and actually downward during the remainder. There 90 are various other ways in which a stress can be applied to the lift span in different directions as the latter rises.

The main counterbalancing schemes illustrated are in effect parts of the lifting apparatus. Various other lifting means may be used which impose varying loads on the span as it rises, and such variations may be counterbalanced completely or to the desired extent by the present invention. In fact, 100 whenever there is a variation on the load of the lift span in rising, the present improvement may be used to counterbalance it. In fact, where the arrangement is such as to exert an upward pull on the lift span at all 105 times, merely changing the directions and the vertical components of such pull, as in Fig. 1 for example, the weights 8 and cables 6 may

be so proportioned and arranged as to eliminate the main counterweighting system referred to. The weights 8 in that case would have a counterbalancing effect to the full extent desired in the lower position of the span and as the cables 6 run over the pulleys and provide an increased load, tending to lift the span, such increase would be counterbalanced by the change in the direction of application of the load and the consequent diminution in the vertical component of the applied stress.

The same counterweight principle may be applied to various other structures having heavy parts which are moved up and down in straight vertical lines like the vertical lift bridge illustrated. And it will be understood that the drawings herein are chiefly diagrammatic and that where two weights 8 with their cables are shown, there may be any number of such units arranged at locations where the strains can be best applied to the lift span; and that the same holds true in the application of the invention to other structures.

Various modifications may be made by those skilled in the art without departing from the invention as defined in the following claims.

30 What I claim is:

1. A lift bridge including in combination a pair of towers, a vertical lift span which rises in a straight line between said towers, main counterbalancing means acting on the ends of the span and imposing varying loads on it as it rises and supplementary means separately connected to the span for counterbalancing such variation.

2. A lift bridge including in combination a pair of towers, a vertical lift span between said towers, main counterbalancing means comprising cables connected to the ends of the span and running over supports on said towers and carrying counterweights and supplementary means for counterbalancing the variation in the load imposed on the span by said cables as the span rises, said supplementary means comprising cables separately connected to the ends of the span and carrying counterweights.

3. A vertical lift bridge including in combination a lift span which rises in a straight line and counterbalancing means for applying a pull in different directions to the span as the latter rises.

4. A vertical lift bridge including in combination a lift span which rises in a straight

line, a counterweight, a cable leading therefrom over a guide to a point on the span, the guide and said point being so located with relation to each other as to apply the pull of the cable to the lift span in different directions as it rises.

5. A vertical lift bridge including in combination a lift span which rises in a straight line and counterweighting means comprising a weight and a cable leading therefrom over a guide to a point on the lift span outside of the vertical line through the guide so as to apply the pull to the span in different directions as the span rises.

6. A vertical lift bridge including in combination a lift span which rises in a straight line and lifting means therefor adapted to impose varying loads on the span as it rises and counterbalancing means for applying a pull in different directions to the span as the latter rises.

7. A vertical lift bridge including in combination a lift span which rises in a straight line having a main counterbalancing system which imposes varying loads on the span as it rises and supplementary counterbalancing means for applying a pull in different directions to the span as it rises.

8. Counterbalancing apparatus for lift bridges or the like having a rising part which moves upward in a straight line, said counterbalancing apparatus comprising means for applying a pull to the rising part of the structure in different directions as it rises.

9. Counterbalancing apparatus for lift bridges or the like having a rising part which moves upward in a straight line, said counterbalancing apparatus comprising a weight and a cable leading therefrom over a guide and to the rising part of the structure, the guide and said point being so located with relation to each other as to apply the pull of the cable to said rising part in different directions as it rises.

10. Counterbalancing apparatus for lift bridges or the like having a rising part which moves in a straight line, said counterbalancing apparatus comprising a weight and a cable leading therefrom over a guide and to a point on the rising part of the structure which is outside of the vertical line through the guide so as to apply the pull to said part in different directions as it rises.

In witness whereof, I have hereunto signed my name.

SHORTRIDGE HARDESTY.
